Primary Examiner — Cynthia Underwood(74) *Attorney, Agent, or Firm* — Loza & Loza, LLP; Michael I. Angert(57) **CLAIM**

We claim the ornamental design for a mounting enclosure, as shown and described.

DESCRIPTION

FIG. 1 is top front left side perspective view of a mounting enclosure showing our new design;

FIG. 2 is a front side elevational view of the mounting enclosure of FIG. 1;

FIG. 3 is a rear side elevational view of the mounting enclosure of FIG. 1;

FIG. 4 is a left side elevation view of the mounting enclosure of FIG. 1;

FIG. 5 is a right side elevation view of the mounting enclosure of FIG. 1;

FIG. 6 is a top plan view of the mounting enclosure of FIG. 1;

FIG. 7 is a bottom plan view of the mounting enclosure of FIG. 1; and,

FIG. 8 is a cross-sectional view of the mounting enclosure of FIG. 1, taken through the plane 8-8 identified in FIG. 2.

The broken lines shown in the drawings are included for the purpose of illustrating environmental structures and from no part of the claimed design. The dash-dot-dash line identified as 8-8 in FIG. 2 is included for the purpose of illustrating a cutting plane and forms no part of the claimed design.
